ORRIN MORSE, OF ROCHESTER, NEW YORK, ASSIGNOR TO C. H. MORSE AND COMPANY OF SAME PLACE.

Letters Patent No. 80,203, dated July 21, 1868.

IMPROVEMENT IN COAL-SCUTTLES.

The Schedule referred to in these Letters Patent and making part of the same.

TO ALL WHOM IT MAY CONCERN:

Be it known that I, ORRIN MORSE, of the city of Rochester, county of Monroe, and State of New York, have invented a certain new and useful Improvement in Coal-Scuttles; and I do hereby declare that the following is a full and exact description thereof, reference being had to the accompanying drawings, making part of this specification.

Figure 1 is a perspective view, showing two of my improved scuttles as packed together.

Figure 2, a diagram, showing the nose or discharge-end of the scuttle in the position for turning coal into a stove-door.

Like letters of reference indicate corresponding parts in both figures.

My invention consists in a peculiar formation of the bonnet or shield, whereby the scuttles are enabled to pack for transportation and storage, and, when raised to the door or opening of a stove, in proper position to discharge coal, the nose stands on a parallel line, or nearly so, with said opening.

In the accompanying drawings, A indicates the scuttle, which has nothing peculiar in its construction, and B represents the bonnet or shield, which is placed over the top of the front portion, to retain and direct the coal in its discharge.

In ordinary scuttles having bonnets, the bonnet, at its rear or widest part, passes in a straight vertical line from side to side, thereby covering so large a portion of the top opening of the scuttle that one cannot be placed in another for transportation or storage. This is shown by the red line at the top in fig. 1. In ordinary scuttles, also, the front of the bonnet projects outward to such a degree that the nose or discharge-spout stands at right angles, or nearly so, to the upper and under incline, in which case, when the nose is inserted in the vertical door or opening of a stove, the upper portion will project in and the lower part draw out of the opening, thereby making it difficult to discharge the coal without spilling. This is indicated by the red line in fig. 2.

I obviate these difficulties by cutting away both the rear and front portions of the bonnet in concave or square form, *c. e.*, fig. 1, and to such a degree that the scuttles will pack in the manner indicated in fig. 1, and, when elevated, to discharge the coal at a side opening, the edge of the nose will stand parallel, or nearly so, to the opening, as indicated in fig. 2.

By this means, while the bonnet is as effective as the old device in preventing spilling of the coal, and there is much saving in the cost of manufacture, a much more convenient article is produced for general use, and one where there is no difficulty in packing.

What I claim as my invention, and desire to secure by Letters Patent, is—

A coal-scuttle, having the bonnet cut away on both sides, in such a manner and to such a degree as to enable the devices to pack and to discharge coal properly in a side opening, as specified.

In witness whereof, I have hereunto signed my name in the presence of two subscribing witnesses.

ORRIN MORSE.
